UNITED STATES PATENT OFFICE.

ROMANTA D. WOODFORD, OF CORTLAND, NEW YORK.

DESIGN FOR A BRACE FOR CARRIAGE RUNNING-GEAR.

SPECIFICATION forming part of Design No. 35,762, dated February 18, 1902.

Application filed August 21, 1901. Serial No. 72,858. Term of patent 7 years.

To all whom it may concern:

Be it known that I, ROMANTA D. WOODFORD, a citizen of the United States, and a resident of Cortland, in the county of Cortland and State of New York, have invented and produced a new and original Design for a Brace for Carriage Running-Gear, of which the following is a specification, reference being had to the accompanying drawings, forming part thereof.

Figure 1 is a top or plan view of the brace. Fig. 2 is a perspective view of the same. Fig. 3 is a view in side elevation of the same. As shown in the drawings, the leading or material feature of my design resides in a brace which has a single curve in one direction when viewed from various points—that is, from the top, from the side, or from the end. This brace terminates at one end in a broadened portion and at the opposite end in a flattened portion somewhat cylindrical in outline.

A distinguishing feature of the design re-

sides in the appearance of reversed curves when viewed in perspective, as seen in Fig. 25 2 of the drawings. When viewed in end elevation, the brace extends for a certain distance in a somewhat straight line and then sweeps downward in a curve; but when viewed in side elevation the curve is practically continuous from end to end. When viewed in plan, as seen in Fig. 1, the brace extends for some distance in a somewhat straight line and then sweeps to one side.

Having described my invention, what I 35 claim as new, and desire to secure by Letters Patent, is—

The design for a brace for carriage running-gear as herein shown and described.

In testimony whereof I have signed my 40 name to this specification in the presence of two subscribing witnesses.

ROMANTA D. WOODFORD.
